ISAAC SNOW, OF LAWRENCE, MASSACHUSETTS.

SHUTTLE.

1,375,187.

Specification of Letters Patent. Patented Apr. 19, 1921.

Application filed April 17, 1919. Serial No. 290,821.

To all whom it may concern:

Be it known that I, ISAAC SNOW, a citizen of the United States, residing at Lawrence, in the county of Essex and State of 5 Massachusetts, have invented certain new and useful Improvements in Shuttles, of which the following is a specification.

My invention relates to an improvement in shuttles, more particularly of the self-threading type for weft replenishing looms.

The object of my invention is to provide a threading guide of simple construction that can readily be located in a threading chamber, one in which the operation of self 10 threading may be performed with certainty and one in which, when threaded, dethreading will be impossible or very improbable.

Other purposes of my invention are to reduce the likelihood of ballooning by the 15 thread and the elimination of all points, beaks, or other projecting parts in any position where a loop of the thread can catch or loop around them.

For convenience and for the purpose of 20 identification in this specification, I will call the "front", that end of the shuttle where the eye is located, and the other end of the shuttle the "back".

I will call an eye which passes out of the 25 left side when looking at the front point, a "left eye", and an eye on the opposite side, a "right eye".

In all the figures of the drawings except 30 Figure 10, I show a shuttle with a left eye, and in all the figures the yarn on the bobbin is supposed to be wound in the usual 35 way, shown in Fig. 1, that is, from left to right it goes over, thence down under from right to left.

I will call the top of the shuttle as it runs 40 in a loom as the "top side", and the bottom as the "bottom side".

In the drawings, Fig. 1 is a plan view 45 of the front end of a shuttle with a metal threading block to which it is attached, and in which is embodied my device. Fig. 2 is an elevation from the left of Fig. 1. Fig. 3 is a view similar to Fig. 2 of a threading block including my device, the shuttle being 50 indicated by dotted lines. Fig. 4 is a section on line 4—4 of Fig. 1 looking from the left, that is, in the direction of the arrows. Fig. 5 is a front elevation of a shuttle with my device attached. Fig. 6 is a side elevation of 55 a threading block, including my device, from the side opposite to that shown in

Fig. 3. Fig. 7 is a front elevation, and Fig. 8 a rear elevation of Fig. 6. Fig. 9 is a section from the top on line 9—9 in Fig. 7. Fig. 10 is a front perspective view of my device embodied in what might be called a sheet metal threading block, of somewhat modified form from that shown in Figs. 1 to 9. Fig. 11 is a plan view of the front of a shuttle with my guide plate attached directly to 60 the wood of the shuttle, the usual form of threading block being omitted. Fig. 12 is a sectional elevation from the front in the direction of the arrow on line 12—12 of Fig. 11.

S is a shuttle having the usual bobbin chamber 10 for the bobbin B from which the yarn or thread A is unwound. 12 is the threading chamber which extends forward in continuation of bobbin chamber 10, and 70 13 is the delivery passage which extends still farther forward from the threading chamber. H represents the shuttle eye in the wood, and this connects with the threading chamber 12 through the slot 15 and the slot 80 14 cut away from the delivery passage 13. The usual bearing pins 17, 17 are shown.

My invention consists essentially of the 75 thread directing guide plate G which, in Figs. 1 to 9, is shown as attached to, by 80 being set into, a threading block F.

I find a convenient method of applying 85 my guide plate is to a threading block, such as F, which has at the front end a horn 32, at the bottom a projection 34 which sets into 90 a recess in the wood of the shuttle in a well known manner, and a hole 35 for the retaining bolt or screw 36.

This thread directing guide plate G has a 95 nose 19 which extends forward of the shuttle eye outlet H, and at 22 slopes down and back from the nose through the threading chamber 12. This side 22 slopes down and out toward the side of the shuttle from the top part shown at 21, preferably from the 100 side of the eye in the same direction and proximate the normal unwinding path of the yarn as it unwinds on the first pick of the shuttle in a magazine loom.

This top part, which is shown as bent over 105 to form a top rim 20 to fit into a suitable groove 37, extends lengthwise of the top 30 of threading block F whereby it is attached to block F which may be considered as part of the shuttle. Preferably, this rim 20 is 110 brazed or soldered into the groove 37.

Near its back, bottom edge 26 of guide

plate G is bent under, forming a thread retaining guide hook 24 which is preferably of involute form and extends up at a point back of the shuttle eye and proximate to the 5 bobbin chamber. It is preferably of such length as to overlap guide plate G and preferably is cut away at the back so as to rake forward.

Directly in front of this hook 24 is an 10 open space 25 which may continue out to the nose 19, but I prefer to bend over the bottom edge of the guide plate to form a hooked rim 27 which extends under the sloping forward 15 part of the thread directing guide to a point in front of the shuttle eye and preferably up to the nose 19. This is preferably cut away at the front and back to rake forward and back.

The threading block F is partly of a well 20 known form, being of somewhat triangular shape, and has a forward edge 31, which becomes part of the head or extension from horn 32 of well known type. Preferably the metal at 6 extends forward curving down in 25 side slope 22 as shown in Figs. 4, 5 and 7. I also show a thread pin 33 around which the thread A passes when the shuttle is correctly threaded.

I prefer that my involute thread retaining 30 hook guide 24 should be so cut away from the rear that it will rake forward, as clearly shown in Fig. 4, and will taper either to a blunt or sharp point, and I prefer that my trapping rim 27 should be cut away at its 35 front and back, both for the purpose of causing loops formed by the ballooning or throwing of the yarn to clear themselves.

In the operation of my device, the thread A is held in a magazine loom beyond the 40 front end 8 of a shuttle, and as the shuttle recedes the thread or yarn rapidly unwinds from the bobbin B, traveling in a path which may be likened to a cone which bellies to some extent. The yarn flying over the sloping side of my guide plate naturally follows 45 it and slips down under and into the thread trapping rim 27, if such is used. As it is now caught in the nose or mouth at the front of rim 27, the apex of its cone of revolution 50 is brought nearer to involute hook 24, and the thread is trapped, so to speak, and slips more easily over such hook.

This mouth 101 of rim 27 controls the ballooning or bellying of the thread, and 55 also holds it up under the top of the guide plate so that, when the shuttle stops, any loop formed by the slackening of the thread drops down into the delivery passage 13 or grooves 14 and 15 where it can do no harm. 60 Such holding up, in fact, helps it to drop into the grooves 14 and 15 on the second pick when the shuttle is returning and tends to overcome any tendency to go over to the right and unthread.

65 By making my guide plate G of trumpet

shape with the top edge of trapping rim 27 above nose guard 6, and by making the curl of rim 27 and mouth 101 small, the ballooning of the thread is limited and its tendency to throw or loop is greatly reduced. 70

Generally, during the first pick, the thread runs through the guide hook 24 and trapping rim 27, while on the second pick it slips over the cut-away front edge of rim 27 and passing through the open part 25 of the bottom edge of guide plate G, it runs out through the shuttle eye H around the friction pins 33. 75

If, on account of ballooning or for any other cause, the thread slips out of the eye H 80 and back through the passages 14 and 15, it will ordinarily be trapped by the rim 27, but if it escapes, it will pass out the other way under through the open space 25, still being held by involute hook 24, and on the 85 next throw of the shuttle will rethread.

When, as sometimes happens, the yarn balloons and loops forward over the nose 19, as shown in Fig. 6, the loop will slip down off the guide plate and the rim 27 onto the 90 hook 24, as shown in Fig. 4, and from thence will slip off the end, thus clearing itself. 95

To facilitate this clearing of loops, I prefer to form the rear edge 25 of the thread directing guide so as to slope down and forward, as shown in Fig. 6, or I may cut away the nose, as shown at 66 in Fig. 11, or I may do both. In any event, the edges of the guiding parts should be so cut that any loops will naturally clear themselves as the shuttle 100 moves in its regular course.

As shown in the slightly modified form shown in Fig. 3, I may cut the metal of block F away squarely at 38 behind horn 32 so that a piece of felt 39 or other suitable material can be introduced as a friction. Preferably, this is pressed in behind the bearing pin 33. 105

While I prefer to use my device on shuttles with a left eye and a bobbin with the 110 normal winding, as shown in Fig. 10, it can be applied to a right eye and, instead of being attached to a cast or forged threading block, the guide plate and block can all be made of sheet metal, as shown at L in 115 Fig. 10.

In Fig. 10, a suitable blank is cut and bent so that the bottom wall 51 and side walls 50 and 53 will fit into a suitable threading chamber. Preferably, a block 52 is interposed to keep side walls 50 and 53 the right distance apart, and the device is held in place as by means of a bolt passed through a hole 35. 120

The guide plate proper is formed by bending over the side wall 50 at 57, and the involute hook 59 is farther bent therefrom at the rear proximate the bobbin chamber. The front edge 58 is shown as sloping down and back from the nose 70 and down and for- 125

ward from the back 71. The other side 53 is formed at its front as the horn 54, behind which the thread passes out through a right eye, and is bent over in substantially T shape 5 to form a longitudinal rim 56, and is cut away and bent over and back at 55 to register with a thread directing slot or passage, such as 14 or 15. The operation is substantially the same as in the other construction 10 with a left eye, the thread block, however, and the trapping rim 27 being omitted.

In Figs. 11 and 12, I show a very simple form of my guide plate at M. The shuttle has the slot or passage 15 cut in the wood, 15 as well as the bobbin chamber 10 and the threading chamber 60, together with the delivery passage 13. The right wall 61 of the threading chamber is substantially straight, as shown in Fig. 11. The top rim 20 63 of guard plate M fits into a suitable channel 75 in the wood and is shown as held in position by screws or brads 64. It slopes on the side, it has a snub nose 66 at the front and at the side 65 slopes down and out, and 25 the edge of this side slopes from the front down and back and, from the back, down and forward at 68. The side 65 is extended to form the involute thread retaining hook guide 67, which is shown as raking at 30 each edge forward. In this construction the trapping rim is shown as omitted, although it is manifest that it might be included.

I prefer to make the front end or mouth 35 of the trapping rim and guide plate, which comes under the nose 19, relatively small, and to form the rest of the guide plate, including guide slopes 22 and the guide hook 24, substantially in the form of a trumpet, 40 the part 25 in front of the hook being cut away preferably as far as the bottom or a little farther. I also prefer to make the nose 19 rounded, as also the front and back of trapping rim, the back edge 125 of the 45 guide plate and the back edge of the involute hook 24, all sloping in the direction which the thread is to take in threading. The front edge of the involute hook is preferably in a plane at right angles to the axis 50 of the shuttle, or it may hook forward, as shown in Fig. 11. If the yarn unthreads, it will run out through the cut-away part 25 out around the outside of the sloping part 22 of the guide plate G, in which case it 55 will be effectively held in position, or it will slip back up around the trapping rim 27, where it will also be held in position.

It is to be understood that my device can be constructed and attached in various ways. 60 It may be attached to the wood of the shuttle, which has been cut suitably to receive it, or to a metal threading block, which amounts to the same thing, in any suitable manner.

65 My device consists essentially of a guide

plate, preferably of sheet metal, attached by means of an attaching rim near the top of the shuttle and extending over at a suitable slope into the threading chamber, in the direction in which the thread will unwind 70 from the bobbin, such guide plate raking backward along its front edge from its nose and preferably forward from its back edge, the sloping side merging into a hook guide preferably of involute form, there being no 75 place for the thread to go except around the slope and into the hook. The mouth of the passage leading into the hook is the whole top of the threading chamber and preferably narrows down so that as the 80 thread travels it is guided naturally and inevitably into the hook. When once in the hook it remains there, as the hook guide forms the termination of a continuous slope or curve from the top side of the threading 85 passage.

Additional features are the trapping rim which rakes forward and back, the forward rake of the back of the guide hook, the trumpet shape of the whole guide plate with 90 the small mouth of the trapping rim, and the nose guard which projects down so as to be in front of the upper edge of the trapping rim.

I claim:

1. The combination in a shuttle having an eye, a bobbin chamber, a threading chamber in continuation thereof which connects with the eye, and a delivery passage extending forward from the threading chamber, of a thread directing guide plate 100 so fixed to the top side of the shuttle as to extend into the threading chamber, such guide plate having a nose which extends forward of the eye and having a bottom 105 rim which slopes down and back from the nose and down and forward from the back through the threading chamber and at the side slopes down and out, with an involute thread retaining hook guide which extends 110 from and under the thread directing guide plate back of the shuttle eye and proximate the bobbin chamber, such hook being cut away to rake forward and to taper, and a thread trapping rim which extends under 115 the sloping forward part of the thread directing guide in front of the shuttle eye and is cut away at its front and back.

2. The combination in a shuttle having an eye, a bobbin chamber, a threading chamber 120 in continuation thereof which connects with the eye, and a delivery passage extending forward from the threading chamber, of a thread directing guide plate so fixed to the top side of the shuttle as to extend into the 125 threading chamber, such guide plate having a nose which extends forward of the eye and having a bottom rim which slopes down and back from the nose and down and forward from the back through the threading chamber 130

ber and at the side slopes down and out, with an involute thread retaining hook guide which extends from and under the thread directing guide plate back of the 5 shuttle eye and proximate the bobbin chamber, such hook being cut away to rake forward and to taper.

3. The combination in a shuttle having an eye, a bobbin chamber, a threading chamber in continuation thereof which connects with the eye, and a delivery passage extending forward from the threading chamber, of a threading block fixed to the shuttle in the threading chamber, and having a longitudinal groove in its top part, a thread directing guide plate of sheet metal having an attaching rim at its top edge which sets into said groove and is so fixed therein that the guide plate extends into the threading 15 chamber, such guide plate being of substantially trumpet shape, having a nose which extends forward of the eye and having a bottom rim which slopes down and back from the nose and down and forward from 20 the back through the threading chamber and at the side slopes down and out, with an involute thread retaining hook guide which extends from and under the thread directing guide plate back of the shuttle eye 25 and proximate the bobbin chamber, such hook being cut away to rake forward and to taper, and a thread trapping rim which extends under the sloping forward part of the thread directing guide in front of the shuttle eye and is cut away at its front and back, together with a nose guard which extends 35 down in front of the top edge of the trapping rim.

4. The combination in a shuttle having an eye, a bobbin chamber, a threading chamber in continuation thereof which connects with the eye, and a delivery passage extending forward from the threading chamber, of a thread directing guide plate so fixed to 40 the top side of the shuttle as to extend into the threading chamber, such guide plate having a nose which extends forward of the eye and having a bottom rim which slopes down and back from the nose through the 45 threading chamber and at the side slopes down and out, with an involute thread retaining hook guide which extends from and under the thread directing guide plate back of the shuttle eye and proximate the bobbin chamber, such hook being cut away to 50 rake forward and to taper.

5. The combination in a shuttle having an eye, a bobbin chamber, and a threading chamber in continuation thereof which connects with the eye, of a thread directing 55 guide plate so fixed to the top side of the shuttle as to extend into the threading chamber, such guide plate having a nose which extends forward of the eye and having a bottom rim which slopes down and back 60

from the nose through the threading chamber and at the side slopes down and out, with an involute thread retaining hook guide which extends from and under the thread directing guide plate back of the shuttle eye 70 and proximate the bobbin chamber, such hook being cut away to rake forward and to taper.

6. The combination in a shuttle having an eye, a bobbin chamber, and a threading chamber in continuation thereof which connects with the eye, of a thread directing guide plate so fixed to the top side of the shuttle as to extend into the threading chamber, such guide plate having a nose which extends forward of the eye and having a bottom rim which slopes down and back from the nose through the threading chamber and at the side slopes down and out, with an involute thread retaining hook 80 guide which extends from and under the thread directing guide plate back of the shuttle eye and proximate the bobbin chamber 85.

7. The combination in a shuttle having an eye, a bobbin chamber, and a threading chamber in continuation thereof which connects with the eye, of a thread directing guide plate so fixed to the top side of the shuttle as to extend into the threading chamber, such guide plate having a bottom rim which slopes down and back through the threading chamber and at the side slopes down and out, with an involute thread retaining hook guide which extends from and under the thread directing guide plate back of the shuttle eye. 90

8. The combination in a shuttle having an eye, a bobbin chamber, and a threading chamber in continuation thereof which connects with the eye, of a thread directing guide plate so fixed to the top side of the shuttle as to extend into the threading chamber, such guide plate having a bottom rim which slopes down and back through the threading chamber and at the side slopes down and out, with a thread retaining hook 105 guide which extends from and under the thread directing guide plate back of the shuttle eye. 110

9. The combination in a shuttle having an eye, a bobbin chamber and a threading chamber in continuation thereof which connects with the eye, of a thread directing guide plate so fixed to the top side of the shuttle as to extend into the threading chamber, such guide plate having a thread trapping rim which extends from and under its forward part and a thread retaining guide hook which extends from and under its 120 back part. 125

10. The combination in a shuttle having an eye, a bobbin chamber, and a threading chamber in continuation thereof which connects with the eye, of a thread directing 130

- guide plate so fixed to the top side of the shuttle as to extend into the threading chamber, such guide plate having a bottom rim which slopes down and back from the front and down and forward from the back through the threading chamber and at the side slopes down and out, and a thread trapping rim of hook form which extends from and under the sloping forward part of the thread directing guide. 10
11. The combination in a shuttle having an eye, a bobbin chamber, and a threading chamber in continuation thereof which connects with the eye, of a thread directing guide plate so fixed to the top side of the shuttle as to extend into the threading chamber, such guide plate having a bottom rim which slopes down and back from the front and at the side slopes down and out, and a thread trapping rim of hook form which extends from and under the sloping forward part of the thread directing guide. 15
12. The combination in a shuttle having an eye, a bobbin chamber, and a threading chamber in continuation thereof which connects with the eye, of a thread directing guide plate so fixed to the top side of the shuttle as to extend into the threading chamber, such guide plate having a bottom rim which slopes down and back from the front and at the side slopes down and out, and a thread trapping rim of hook form which extends from and under the sloping forward part of the thread directing guide, and is cut away at its front and back. 30
13. The combination in a shuttle having an eye, a bobbin chamber, a threading chamber in continuation thereof which connects with the eye, and a delivery passage extending forward from the threading chamber, of a thread directing guide plate so fixed to the top side of the shuttle as to extend into the threading chamber, such guide plate having a nose which extends forward of the eye and having a bottom rim which slopes down and back from the nose and down and forward from the back through the threading chamber and at the side slopes down and out, with an involute thread retaining hook guide which extends from and under the thread directing guide plate back of the shuttle eye and proximate the bobbin chamber, such hook being cut away to rake forward and to taper, and a thread trapping rim which extends under the sloping forward part of the thread directing guide in front of the shuttle eye and is cut away at its front and back whereby the yarn is guided over such guide plate up into the trapping rim and hook guide during the first pick and leaves the trapping rim during the second pick. 60
14. The combination in a shuttle having an eye, a bobbin chamber, and a threading chamber in continuation thereof which connects with the eye, of a thread directing guide plate so fixed to the top side of the shuttle as to extend from the side of the eye into the threading chamber, such guide plate having a bottom rim which slopes down and back through the threading chamber and at the side slopes down and out, with a thread retaining guide hook which extends from and under the thread directing guide plate back of the shuttle eye, said hook guide and sloping side of the guide plate extending in the same direction and proximate the normal unwinding path of the yarn as it unwinds on the first pick of the shuttle in a magazine loom. 70
15. The combination in a shuttle having an eye, a bobbin chamber, and a threading chamber in continuation thereof which connects with the eye, of a thread directing guide plate so fixed to the top side of the shuttle as to extend into the threading chamber, such guide plate having a bottom rim which slopes down and back through the threading chamber and at the side slopes down and out, with a thread retaining guide hook which extends from and under the thread directing guide plate back of the shuttle eye, said hook guide and sloping side of the guide plate extending in the same direction and proximate the normal unwinding path of the yarn as it unwinds on the first pick of the shuttle in a magazine loom. 80
16. The combination in a shuttle having an eye, a bobbin chamber, and a threading chamber in continuation thereof which connects with the eye, of a thread directing guide plate so fixed to the top side of the shuttle as to extend into the threading chamber, such guide plate sloping down and out through the threading chamber and having a thread trapping rim which extends from and under its forward part and a thread retaining hook guide which extends from and under its back part, said hook guide and sloping side of the guide plate extending in the same direction and proximate the normal unwinding path of the yarn as it unwinds on the first pick of the shuttle in a magazine loom. 100
- In testimony whereof I have affixed my signature. 110

ISAAC SNOW.
